UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

BEARING FOR YARN SPOOLS AND THE LIKE.

Application filed May 20, 1922. Serial No. 562,453.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Bearings for Yarn Spools and the like, of which the following is a specification.

The present invention relates to journal 10 bearings and is particularly intended for use in retaining the journals of yarn spools in operative position for rotation in a tube frame while making simple and reliable provision for quick and convenient removal 15 of the spools from their bearings with a minimum of lost time or lost motion in the operation, while preferably requiring the use of but one hand so as to leave the other hand free to handle the yarn spool.

20 As is well known in the art, tuft tubes for weaving pile fabrics of considerable width, such as Axminster rugs, are provided with yarn-carrying spools made in longitudinal sections which are aligned along a 25 common axis to rotate in unison by means of interlocking end engagement, each section being journaled at its opposite ends in properly aligned bearings mounted on the tube frame. As frequent removal of one 30 or all of these sections is necessary it is highly desirable that such removal shall be made very quickly and easily but without sacrificing absolute security of the bearing mounting of the spool since the accidental release of the spool, during the weaving 35 operation, would involve a great deal of damage and lost labor in repairing the mischief.

With these objects in view, the present 40 invention consists, generally speaking, of the combination of two cooperating pivotally connected bearing members provided with segmental bearing recesses arranged to form a complete journal bearing for the reception and retention of a spool journal or trunnion when the members are in operative or closed relationship while permitting their instant separation preferably by means of practically a single movement of one hand, locking means being provided to securely 45 hold the bearing members in closed relation and to be released in the act of seizing one 50

of said members to open the bearing for the removal of the spool therefrom. A further feature of the invention is that the 55 closing of the bearing acts to automatically lock the bearing members once more in operative or closed relation, thereby avoiding any damage that might be caused by the neglect of the operator to himself attend to 60 the locking of the bearing.

These and other features of the invention will be particularly explained in the following specification and will be defined in the claims hereto annexed.

In the accompanying drawings I have illustrated several of the forms of construction and arrangement used in the embodiment of the principles of this invention in which:

Figure 1 is a side elevation of a complete bearing structure with one side of the supporting bearing bracket removed.

Figure 2 is an elevation taken at right angles to the plane of Figure 1 on the direct 75 line 2—2 of Figure 1.

Figure 3 is an end view of the complete device.

Figure 4 is a side elevation showing the locking latch released ready to permit the 80 opening of the bearing.

Figure 5 is a side elevation showing the bearing completely open.

Figure 6 is a perspective view of a slightly modified form of the invention.

Figure 7 is a detail view of the segmental bearing bushing.

Figure 8 is a side elevation showing another modification of the invention.

Figure 9 is a view at right angles to the 90 plane of Figure 8.

Figure 10 is a side elevation showing the latch released ready to permit the opening of the bearing.

Figure 11 is a detail view of a modified 95 form of bushing.

In the practice of this invention, according to the form illustrated in Figures 1 to 5, I provide a suitable bracket or support for the bearing members which includes two parallel standards or plates 1, having right-angled base flanges 2, to form supporting feet by which they are secured to 100 the tube frame or other device upon which

the device is to be used. These parallel spaced plates carry at their upper ends a semi-circular bushing 3 formed with an external medial rib 4 forming a separating 5 or spacing shoulder interposed between the notched or recessed outer ends of the bracket plates 1, and secured thereto in any suitable manner as by spinning over the opposite thin side edges, the end edges of the 10 bearing bushing being held in place by hook-like projections 1^a overhanging the opposite ends of the bushing. Any suitable method, however, of securing the bushing in place may be used. Mounted in this bearing 15 is a transverse fulcral pin or axle 5, and a transverse stop pin 6. On the transverse fulcral pin 5 are pivotally mounted two similarly formed bearing arms or members 7 segmentally recessed as at 8 to complete the circle around the journal of a spool to effectually retain said journal in 20 position for rotation in said bearing. The principal thrust of the bearing comes upon the bushing member 3, while the overhanging 25 projecting ends of the pivotally mounted arms 7 act as keepers to prevent the journal from being knocked or pulled out of its bearing.

The similar bearing members 7 are spaced 30 apart and carry a transverse pivotal latch pin 9 for supporting between the parallel bearing members or plates 7 an interposed latch member 10 which has bearing support upon said pin and has a downward extension formed with a stop shoulder as 35 shown at 11 to normally rest against the transverse stop pin 6 against which it is pressed by means of a spring 13 engaging the extension 12 of the rear end for that 40 purpose.

Since the latch is mounted eccentrically of the fulcral axis 5 on which the pivotal bearing members 7 are supported, and since the stop pin 6 is so disposed as to prevent 45 rotation in a contraclockwise direction (Figures 1, 4 and 5) it will be understood that no releasing or opening movement of the bearing members 7 is possible until the stop shoulder 11 of the latch 10 is disengaged from or moved out of line with the stop pin 6. This release of the latch is accomplished in the forms shown in Figures 1 to 6 inclusive, by pressure against the upper or free end of the latch 10 which, as shown 50 in Figure 1, normally is wider than the corresponding portion of the arm 7 and projects beyond said arm so that pressure against the latch 10, tending to move it in the direction that arms 7 must swing to open 55 the journal bearing, which tends to release the latch from locking position and allow the pivoted bearing members to swing away to uncover the journal and allow the spool to be removed from its bearings.

60 65 It will be seen that the release of the

latch and the opening of the bearing may be effected by a single forward movement in one direction of a single finger of the operative as indicated in Figure 4, as the first part of said movement releases the latch 70 while the continuation of said movement opens the bearing. On the other hand, when the bearing is open and the finger removed the latch is pressed back against the stop pin 6, but in view of the approach of the 75 pivotal axis of the latch nearer to the stop pin by the opening movement of the bearing member 7, the shoulder 11 is not engaged with the stop pin. In the open position, therefore, the latch will still have its right-hand edge advanced beyond the corresponding edge of the arm 7. In this position the removal of the journal forces the latch back against its tension spring 13 thereby permitting withdrawal of the spool, and also permitting the subsequent insertion of a new spool by pressure of the journal against the latch in open position since the spring 13 allows it to yield under such pressure. The 80 advantage of this arrangement is that when 85 one of the interlocking end journals of a spool section is inserted the latch tends to keep it in place while allowing the interlocking journal of the next spool section to be readily inserted without having to especially manipulate the latch. When both 90 adjacent interlocking journals are in place in the bearing, pressure exerted by the finger as shown in Figure 5, closes the bearing and the latch is automatically pressed by its 95 spring into locking engagement with stop pin 6.

In Figure 6 I have shown a form of invention that is essentially the same as that shown in Figures 1 to 5, but is modified to 105 the extent of using only one pivotal bearing arm 7 on one side of the latch 10 and is further modified by the use of another form of spring 15 which is wound around a supporting post 16 with one end thrusting 110 against the fulcral pin 5 and the other end bearing against the rear end of the latch 10. In both forms of the invention the pivotal bearing arms are transversely formed with a shoulder 7^a to limit the swinging movement thereof in open position, and a similar shoulder is formed at 10^a on the latch 10 to limit the pivotal movement of the latch on its axis.

In the modification shown in Figures 8 to 10 the bracket 1, is of the same construction as before and is provided with a fulcral pin 5 and a stop pin 6 as in the other forms. The form of the pivotal bearing member, however, is somewhat changed although functioning precisely as before. In this form the pivotal bearing member 20, is shaped to receive the thrust of a compressed spring 23 which presses against an extension 21^a of the locking latch 21 so disposed 115

as to cause the spring to tend to produce rotation of the latch 20, on its pivotal axis 9, in the same direction as the direction of rotation of the bearing arm 20, when moving to open position, instead of tending to produce a rotation opposite to the rotative movement of the bearing arm when opening as in the forms shown in Figures 5 and 6. In consequence of this different direction of the releasing movement of the latch it becomes necessary, in order to release the latch, to pinch the upper end of the latch in the opposite direction to the normal opening rotation of the bearing arm 20, preliminary to opening the bearing, as illustrated in Figure 10. The advantage of this arrangement is that an accidental and external blow against the latch that tends to release the latch will not result in opening the bearing since the direction of movement necessary to release the latch is directly opposite to the direction of movement necessary to open the bearing. The pinching action, however, is very conveniently effected by simply compressing this portion of the device between the thumb and finger, as shown in Figure 10, as a part of the opening operation so that no time is lost and only one hand is needed to perform this operation. In this case the bearing bushing 26 is shown without any separating rib or flange to separate the side members 1, of the supporting bracket.

With any of the constructions and arrangements shown it will be obvious that the operator can instantly open the bearing by a single movement of the hand which is so easily performed that his eye-sight and attention can be directed to other parts of the work which demand it, and yet the journals or trunnions of the spools or shafts are securely locked against jarring or accidental blows when the tube frame is in use. This greatly facilitates and expedites the insertion and removal of spools from the tube frame and gives all the required security.

It will be observed that practically all the parts of the device except the spring, may be formed of stamped or pressed metal so that the device can be very cheaply made and assembled, the bearing bushing being preferably used as a convenient means for giving a wide bearing surface for the journals of the yarn spools.

What I claim is:

1. A bearing construction for a yarn-spool journal or the like, embracing in combination two cooperative bearing members pivotally connected to permit movement of one toward and away from journal-retaining relationship to the other, a catch carried by the movable member, said catch being released by the application of pressure in a direction diverse to the direction of the opening movement of the movable

bearing member, whereby the accidental releasing of the catch does not tend to open the bearing, substantially as described.

2. A bearing construction for a yarn-spool journal embracing in combination two bearing members one of which is pivotally connected with the other and movable to and from bearing-closing position, means carried by the pivotal member for positively locking the pivotal member against opening, said means being disposed to move to releasing position without producing any tendency to open the pivotal bearing member through the agency of the releasing pressure applied, substantially as described.

3. A bearing construction for yarn-spool journals, embracing in combination a fixed bearing member, a movable bearing member pivotally connected therewith, a catch mounted on the movable member and being formed to interlockingly engage a fixed stop arranged on the same side of the journal bearing as is the pivotal axis of the pivotal member, said catch acting normally to positively prevent the opening of the bearing until released from said stop, substantially as described.

4. A separable journal bearing device for a yarn spool embracing in its construction a fixed bearing member, a movable bearing member pivotally supported thereby in position to enclose a rotatable spool journal, a pivotal latch mounted on the movable member eccentrically of the pivotal axis of said bearing member and provided with a stop shoulder arranged to engage a stop on the fixed member to prevent rotation of the movable bearing member in a direction to open the bearing, said stop shoulder being movable out of position to engage the fixed stop by rotation of the latch on its own pivotal axis in a direction reverse to the opening movement of the pivotal bearing member, substantially as described.

5. A separable bearing device for a rotatable shaft journal, embracing in its construction a fixed bearing member formed with an open bearing for supporting a rotatable shaft journal, a coacting pivotal bearing member disposed to act in conjunction with a fixed bearing member to confine the shaft journal in operative position, a spring latch mounted on the pivotal bearing member and normally disposed to engage a stop to prevent the opening of the bearing, said latch being releasable from stop position by movement in a direction opposite to the direction of movement of the pivotal bearing member when being swung open, whereby pressure upon the latch tending to release it will not act to open the bearing, substantially as described.

6. A separable bearing device for a yarn spool, embracing in its construction pivotally connected bearing members arranged to

inclose a rotatable shaft journal in operative position for rotation, a latch pivoted upon a pivotal axis mounted upon and movable with one of said bearing members, said latch having its pivotal axis eccentric to and parallel with the fulcral axis of its supporting bearing member and being provided with a portion adapted to normally abut against a stop member to prevent opening of the bearing, while being manually movable out of position to engage said stop when opening the bearing, substantially as described.

7. A separable bearing device for a spool journal, embracing in its construction a fixed member of stamped metal provided with an open bearing bushing, a pivotal stamped metal plate formed to coact with the bearing-bushing to confine a rotatable shaft journal in operative position, and pivotally mounted on said member to permit it to swing away from the bearing-bushing to open the bearing, a sheet metal latch pivotally mounted on said pivotal plate and disposed to engage a fixed stop to normally prevent opening of the bearing, the outer ends of said latch and its pivotal support

ing plate being arranged in juxtaposition to permit them to be operated by the fingers of one hand, substantially as described.

8. A separable bearing device for quick insertion and removal of a spool journal embracing in combination, pivotally connecting bearing members formed to surround a spool journal to keep it in position for rotation, a spring pressed latch pivotally mounted on and movable with one of said bearing members, to normally prevent the opening of the bearing, the latch having an outwardly projecting portion overhanging the journal in proximity to a similar overhanging portion of its supporting bearing member, whereby the pinching together of these two overhanging members releases the latch and permits the bearing member to be swung open, and permits the latch to yieldably overhang the bearing when open sufficiently to act as a yielding keeper to retain an interposed journal seated in the bearing, substantially as described.

In witness whereof, I have subscribed the above specification.

EDGAR F. HATHAWAY
